CLAIM

The ornamental design for a fixed focus microscope with a removable mount for a mobile phone camera, as shown and described.

DESCRIPTION

FIG. 1 is a perspective view of a fixed focus microscope with removable mount for mobile phone camera showing my new design, the fixed focus microscope is shown separately for purposes of illustration;

FIG. 2 is a perspective view of the microscope with the camera mount.

FIG. 3 is a left side view of the microscope without the camera mount.

FIG. 4 is a left side view of the microscope with the camera mount.

FIG. 5 is a top view of the microscope without the camera mount.

FIG. 6 is a bottom view of the microscope without the camera mount.

FIG. 7 is a top view of the microscope with the camera mount.

FIG. 8 is a bottom view of the microscope with the camera mount.

FIG. 9 is a front, elevation view of the microscope without the camera mount.

FIG. 10 is a back, elevation view of the microscope without the camera mount.

FIG. 11 is front, elevation view of the microscope with the camera mount.

FIG. 12 is a front, elevation view of the microscope with the camera mount.

FIG. 13 is a right side view of the microscope without the camera mount; and,

FIG. 14 is a right side view of the microscope with the camera mount.

My microscope is characterized by its vertical eyepiece orientation and its inverted vertical objective lens orientation in a slim housing rounded at either end with a LED light source positioned directly above the objective in a pocketed area of the substantially symmetrical shape. It has a recessed power switch on one side and a recessed label area on the other side. The removable camera mount has a recessed label area and rubber bumpers on the top surface.
